FRANK V. BURTON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ATTACHMENT-PLUG FITTING.

1,073,955.

Specification of Letters Patent. Patented Sept. 23, 1913.

Application filed December 3, 1912. Serial No. 734,700.

To all whom it may concern:

Be it known that I, FRANK V. BURTON, a citizen of the United States of America, and residing at Bridgeport, in the county 5 of Fairfield and State of Connecticut, have invented a certain new and useful Improvement in Attachment-Plug Fittings, of which the following is a specification.

The present invention relates to an attachment plug fitting and particularly to a plug adapted to be combined with various outlet fittings of standard type, especially switched fittings, the object of my invention being to provide a device of novel and 15 efficient utility and construction.

In the accompanying illustrative embodiments of my invention, Figure 1 is a broken elevation partially in section of a combined plug and pull socket, the section through 20 the plug portion being taken on the line 1-1, Fig. 2; Fig. 2 is a plan of the plug alone; Fig. 3 is a section on the line 2-2, Fig. 2; Fig. 4 is a broken perspective of the cap of the plug; Fig. 5 is an elevation 25 of a combined plug and key socket partially broken away to show the latching elements on the socket shell; and Fig. 6 is a similar view of a combined plug and switched rosette.

There are many instances of installations 30 in which outlets are provided without switches to control the circuit tapped off by plug or otherwise at the outlet fitting. In such cases, if the tapped circuit is to be independently controlled, a switch must be installed at some point therein and this is usually arranged at the point at which the circuit is to be used, as for instance at a light. Under certain circumstances it is 35 preferable to control the circuit at the outlet and the present device renders this possible in an installation of the type referred to, by providing a plug fitting which comprises, in combination with the plug, any 40 one of various standard switched fittings, some of which are illustrated herewith.

The present plug which is here shown as a screw plug, has a body comprising two buttons of insulating material A and B, 45 united by a central bolt 10, the head of which, with its washer 11, forms the center contact of the plug. A screw shell 12 surrounds the lower button B, while a flange 13 projecting inwardly over the upper face 55 of the button is clamped between the latter

and the lower face of button A when the screw bolt 10 is tightened. The upper face of the button is recessed to receive terminal plates 14 and 15 each with its binding screw 16 and 17 respectively and separated by the 60 barrier 28. The center contact screw bolt 10 is threaded into the plate 14, while electrical connection is established between plate 15 and the screw shell 12 by a short screw 18 passing through the ear 19 on the 65 flange 13 and screwed into a threaded perforation in the plate 15.

Instead of the usual closure cap for the head of the plug, I mount thereon a peripheral latching ring 20 held in position 70 by off set lugs 21 let into recesses in the upper face of the button A and engaged by screws 29-30 passing up through the latter. In the form shown this latching ring comprises a plain finishing ring, the edges 75 of which are spun over a corrugated inner ring provided with a series of perforations 22 to engage coöperating latching elements on the shell of the coöperating outlet member after the manner of latching elements 80 on the socket cap, shown in the Goodridge Patent No. 958,626.

In the combination illustrated in Fig. 1 a pull socket of any suitable type and provided with a shell having latching elements 85 to coöperate with those of the latching ring 20 is shown in position to be assembled with the plug. Conductors 23, 24 are shown electrically connecting the terminals 16 and 17 on the plug with the terminals 25, 26 90 on the socket, and the current in the latter is controlled by any suitable switch mechanism of the pull type operated by the chain 27. When the socket has been pressed down upon the plug and the coöperating latching 95 elements engaged, as illustrated in Figs. 5 and 6, the combined fitting is ready for installation. Obviously by screwing the plug home in a suitable plug receptacle, an outlet is afforded by the usual contacts of the 100 socket, the circuit through which is controlled by the pull switch in well understood manner.

In Fig. 5 the construction of the plug is the same, but a key, instead of a pull, 105 socket is shown assembled therewith. So in Fig. 6 while the construction of the plug is the same, the switched rosette here shown assembled therewith affords an outlet of different type, but the tapped circuit is con- 110

trollable by a switch at the tap in like manner as in the combinations previously referred to.

The precise details of construction shown may readily be varied, while other combinations with the plug will readily suggest themselves, by which the same result may be achieved.

- I claim as my invention:
10. 1. An attachment plug fitting comprising a plug element having plug and outlet terminals, together with a member on said plug comprising a ring having a series of offset lugs for securing said ring to the head of the plug.
  20. 2. An attachment plug fitting comprising a plug element having plug and outlet terminals, a latching ring with lugs for securing the same on the head of the plug, and

barriers on the head of the plug separating the outlet terminals from each other and from said ring-securing lugs.

3. An attachment plug fitting comprising a plug member having plug terminals on its 25 entering end and latching elements on its outer end, an independent outlet member with latching elements adapted to cooperate with those on the plug, and contacts on the juxtaposed ends of the plug and outlet 30 members electrically connected in the assembled fitting, for the purpose described.

In testimony whereof I have signed my name to this specification, in the presence of two subscribing witnesses.

FRANK V. BURTON.
